UNITED STATES PATENT OFFICE.

CHARLES W. DWELLE, OF ST. LOUIS, MISSOURI.

IMPROVEMENT IN THE MANUFACTURE OF WHITE LEAD.

Specification forming part of Letters Patent No. 95,097, dated September 21, 1869.

To all whom it may concern:

Be it known that I, CHARLES W. DWELLE, of the city of St. Louis, in the county of St. Louis and State of Missouri, have made certain new and useful Improvements in Processes for Manufacturing White Lead and Similar Substances; and I do hereby declare the following to be a full and true description thereof, reference being had to the accompanying drawings, and to the letters of reference marked thereon.

It is well known that usually metallic lead is subjected to the action of carbonic acid in dung-heaps and similar carbonic-acid generators, whereby carbonate of lead is formed. The incrusted salt is then by shaking and sifting devices removed from such metallic lead as may be still remaining unacted upon; and in the usual process of separation the dust of the carbonate is deleterious to health and very difficult of economical manipulation.

For the purposes of a more complete separation of the carbonate, and to avoid wastage of the same, the nature of this invention is in the arrangement of a fan or other suction and forcing device by which the carbonate-dust shall be carried off from the reel or other separator device, and by which said carbonate shall be forced either into proper bags or into water-tanks, as receivers and accumulators therefor; and the nature of this invention is also in the entire arrangement and conjoined action of the various crushing, separating, and elevating devices to be used in the process of manufacture of white lead and similar substances, as will now be more fully explained.

To enable those herein skilled to make and use my said improved process and devices, I will now fully describe the same, referring to the accompanying Figure 1 as a longitudinal sectional elevation; to Fig. 2 as a transverse sectional elevation, showing the devices acting in my said process in one of the more usual forms of its application.

The carbonated-lead cakes or buckles will be received at the base of an elevator, A. Said elevator will have conveyer-buckets arranged in the usual manner upon an endless belt and operated from the power source, so as to carry the carbonate to an upper funnel and discharge the same to the reel B. This will be formed principally of a metal drum with proper perforations, revolving upon a shaft actuated by

proper machinery. By the revolution of the reel the carbonate is separated from such metallic lead as may still be in the cakes, and said carbonate will pass through the perforations of the reel into the surrounding hopper B'. In connection with said hopper is the fan C, formed of a number of fan-blades, which are rapidly rotated upon a shaft in the usual manner. By the suction thus created the finer particles of the carbonate will be drawn to the fan out of the hopper B', to be then carried up the rising pipe D to the distributing-pipe E, usually arranged at the top of the building. Said distributing-pipe E may be connected with bags F, into which the carbonate will fall, or the said pipe may lead to a cistern, G, partially filled with water, for receiving and retaining the carbonate. To prevent loss by the efflux of the air from the water in the cistern G, I arrange a pan, G', near the top hereof, said pan being perforated and receiving the water-supply directly from the supply-pipe. The air will then escape by the annular space between the vertical rim of the pan G' and the cistern-wall. To arrest any dust which might pass here there is a ring, g, curving downward, placed over said annular space as a cover, as more plainly shown in Fig. 1. The heavier particles of carbonate and metallic lead drop into the trough at the base of the hopper B', to be carried forward by a conveyer-screw or similar device, B². The metallic lead not passing through the reel-drum B will be deposited at the tail of the reel upon the floor, to be used with new lead in the ordinary processes. The carbonate delivered from the conveyer-trough falls by the spout H to the rollers I, which, by their revolution, crush and pulverize as well as thoroughly separate out the remaining metallic particles. From said rollers the product is carried by the spout K to a second reel or separator, L. This, as it receives less of the heavy metallic substance, may be built of a light frame, surrounded by a bolt or other screening wire-cloth. By this separator the metal is again thrown out, principally as tailings, while the light carbonate-dust is carried out of the inclosing hopper by a fan or other similar device, M, to be distributed to the bags F or the cistern G, as described. Such droppings as are too heavy for distribution by the fan drop to the trough and conveyer-screw M', to be carried to the base of an elevator, N, which raises said droppings to a fun-

nel, O, to be delivered a second time to the rollers I for pulverization.

It is plain that the operator may by proper management cause the carbonate and its admixtures to pass repeatedly to the crushing-rollers and separators, and thus fully separate out all the carbonate without wastage or undue loss, and that in all said process the carbonate-dust is fairly inclosed and shielded from loss as well as from detrimental action upon the operatives. Lastly, it is especially the finer carbonate-dust which, by its reduced relative specific gravity and bulk, that is here subject to the action of the fans C and M, and which is therefore carried forward to the receivers, while in ordinary processes this finer dust evades all efforts to its retention, and vitiates the air so as to unfit it for respiration.

Having thus fully described my invention, what I claim is—

1. The arrangement of a fan or other suction and forcing device in connection with the separating reels and hoppers, or similar devices, and the combination therewith of bag-receivers or cisterns, substantially as set forth.

2. The eistern G, its pan G', and ring g, when arranged and operating substantially as and for the purposes set forth.

3. The hopper B', its trough, and conveyer, combined with the spout H, rollers I, spout K, and second separator device, L M M', when acting substantially as and for the purposes set forth.

CHAS. W. DWELLE.
